UNITED STATES PATENT OFFICE.

EMIL HANNEMANN, OF HERMSDORF, NEAR BERLIN, GERMANY.

AUTOMATIC FEED-REGULATOR FOR STEAM-BOILERS AND THE LIKE.

1,140,742.

Specification of Letters Patent.

Patented May 25, 1915.

Application filed December 9, 1913. Serial No. 805,484.

To all whom it may concern:

Be it known that I, EMIL HANNEMANN, a citizen of the German Empire, residing at Hermsdorf, near Berlin, in the Kingdom of 5 Prussia, Germany, have invented certain new and useful Improvements in Automatic Feed-Regulators for Steam-Boilers and the like; and I do hereby declare the following to be a full, clear, and exact description of the invention, such as will enable others skilled in the art to which it 10 appertains to make and use the same.

My invention relates to improvements in automatic feed regulators for steam boilers and the like, and more particularly in feed regulators of that class in which the supply of the feed water to the boiler is automatically controlled by means of a fluid operated motor controlled by the level of the 15 water within the boiler and arranged to throw the feed water supply to the boiler into or out of operation. In apparatus of this class such as are now in use the said fluid motor is driven by means of steam 20 taken from the boiler.

One of the objects of the improvements is to provide an apparatus of this class in which a fluid of low pressure is used for driving the motor, so that on the one hand 25 the resistance of the regulating means or valve controlling the supply of the fluid to the motor is reduced, and on the other hand a controlling member such as a float of less power may be employed. Where the said 30 controlling member consists of a float, the size of the float can be made comparatively small, so that it can conveniently be placed into the boiler at any suitable place. Furthermore by reason of the small resistance 35 of the fluid controlling member or valve the action of the float is more reliable and accurate, and almost instantaneous. By reason of the low pressure of the motive fluid the fluid controlling member can more easily 40 be made tight.

A further object of the improvements is to provide an apparatus in which a fluid independent of the steam boiler is used for driving the motor, so that no loss of steam 45 is caused by the controlling member, and no pipes are necessary for withdrawing the motive fluid after acting on the fluid operated motor.

Finally an object of the improvements is 50 to provide an apparatus in which the supply

of the motive fluid to the controlling member can not freeze in cold weather.

With these and other objects in view my invention consists in providing an apparatus in which the motive fluid for operating the 60 motor is supplied independently of the steam boiler, and which for this reason may have any suitable character and any desired low pressure. In putting my invention into effect I use in some cases air or another elastic 65 fluid under pressure or under a vacuum. In other cases I prefer to use a non-elastic fluid, such as water or glycerin, or the like.

In order that my invention be more clearly understood several examples embodying the 70 same have been shown in the accompanying drawings in which the same letters of reference have been used in all the views to indicate corresponding parts.

In said drawings—Figure 1, is a dia- 75 grammatical view partly in section showing my improved regulator in which air under a vacuum is used for driving the motor provided for operating the feed water supply, Fig. 2, is a similar view showing my im- 80 proved apparatus in the form suitable for operation by air or another elastic fluid, and Fig. 3, is a similar view showing my improved apparatus in a form which is suitable for the use of a non-elastic fluid 85 as a driving medium for the motor controlling the feed water supply.

Referring to the example illustrated in Fig. 1, a steam boiler *k* is provided with a feed water supply *l* adapted to be closed or 90 opened by means of a valve *a* of any known or preferred construction. The stem *m* of the said valve is connected with a lever *n* having a rocking support on a bracket or arm *o*. To the said lever a weight or spring *e* is connected which normally tends to force the valve on its seat. At its free end the lever *n* is connected by a link *p* with a suitable fluid operated motor which as shown 95 consists of a piston *q* located within a cylinder *b*. Below the piston the cylinder communicates through a pipe *g* with a pipe *f* comprising a valve box *d*. Within the said valve box there is a double acting valve *r* which is adapted to close or partly close 100 either the pipe *f* or a tubular stud or opening *b* through which the valve casing communicates with the atmosphere. The valve *r* is connected by a stem *s* with an arm *t* secured 105 to a rock shaft *v* extending into a tubular 110

casing w connected with the steam boiler. Internally of the said casing an arm x is keyed to the rock shaft v which is connected by a link u with a float c . The pipe f is connected with an apparatus for producing air or another elastic fluid under a vacuum, such for example as the chimney of the fire place of the steam boiler.

In the operation of the apparatus a vacuum is constantly maintained within the pipe f . While the water level within the steam boiler is at its maximum, the float c permits the valve r to place itself on its lower seat so as to close the suction pipe f and to connect the pipe g and the cylinder b with the atmosphere. Therefore the rocking lever n is free to be held by the spring e in its upper position in which it forces the valve a on its seat, and no feed water is admitted to the boiler.

If the level of the water within the boiler falls, the valve r is unseated, so that the suction within the pipe f is transmitted to the cylinder b and in part to the tubular stud h . Therefore a certain suction is transmitted to the piston g , so that the rocking lever n is rocked downward at a certain angle, until the suction within the cylinder b and the tension of the spring e are at an equilibrium. Therefore the feed water supply valve a is unseated and a certain amount of feed water is supplied through the pipe l and into the boiler. As the level of the water within the boiler falls further, the valve r will gradually close the tubular stud h so that the valve a is further opened by the increased suction within the cylinder b . When the stud h is entirely closed, the valve a is perfectly open, so that a large supply of feed water takes place.

The modification shown in Fig. 2 is designed for operation by means of air or another elastic fluid under pressure. The arrangement of the feed water valve a , the fluid operated motor b , and the float c is substantially the same as has been described with reference to Fig. 1, and the same letters of reference have been used for indicating the said parts, so that a detailed description is not necessary. The spring e' is connected to the rocking lever n at the opposite side of the fulcrum, and the piston g' is normally located on the bottom of the cylinder b . The pipe f' is connected to a supply of air or another elastic fluid under pressure.

In the operation of the apparatus the valve r is normally located on its lower seat so as to close the pressure pipe f' . If the level within the boiler k falls, the valve r is unseated, so that air under pressure is admitted to the motor b so as to force the piston upward against the action of the spring e' . Thereby the valve a is raised from its seat and feed water is supplied to the boiler.

When the level of the water within the

boiler falls further, the valve r closes the stud h , so that the full pressure of the air is transmitted to the cylinder b and the valve a is opened to its full extent.

In the example shown in Fig. 3 a non-elastic fluid is used for operating the motor b . The construction of the apparatus is not materially changed, except that the tubular stud h is provided with a waste pipe y for withdrawing the motive liquid from the cylinder b . Otherwise the operation of the apparatus is not changed and it will readily be understood without further description.

It will readily be understood, that in some cases a non-elastic motive fluid for operating the cylinder b will be preferable, because the action of an elastic fluid is not instantaneous by reason of the elasticity. On the other hand an elastic fluid such as air is preferable, because no waste conduit for withdrawing the fluid is necessary.

I claim herein as my invention:

1. In an apparatus of the class described, the combination with a receptacle, of a liquid supply to said receptacle, a fluid operated motor for throwing said supply into or out of operative position, means counteracting said motor and tending to throw said liquid supply out of operation, means independent of the receptacle to provide a supply of a motive fluid, and means controlled by the level of the liquid within the receptacle to provide an initially slow and subsequently accelerated degree of communication between said motive fluid supply and motor as the liquid level falls below a predetermined position.

2. In an apparatus of the class described, the combination with a receptacle, of a liquid supply to said receptacle, a fluid operated motor for throwing said supply into or out of operative position, elastic means counteracting said motor and tending to throw said liquid supply out of operation, means independent of the receptacle to provide a supply of a motive fluid, and means controlled by the level of the liquid within the receptacle to provide an initially slow and subsequently accelerated degree of communication between said motive fluid supply and motor as the liquid level falls below a predetermined position.

3. In an apparatus of the class described, the combination with a receptacle, of a source of liquid supply for said receptacle, a valve for controlling the communication of said source with the receptacle, elastic means tending normally to maintain the said valve in closed position, a fluid operated motor including a cylinder and a piston movably mounted within the cylinder, and connected operatively with the said valve, a source of supply of motive fluid, and means controlled by the level of the liquid within the receptacle for establishing communica-

tion between one end of motor cylinder and the source of supply of motive fluid and the atmosphere simultaneously at first and then between the said end of the cylinder and the 5 source of supply of motive fluid alone as the liquid level falls below a predetermined position.

4. In an apparatus of the class described, the combination with a receptacle, of a 10 source of liquid supply for said receptacle, a valve for controlling the communication of said source with the receptacle, elastic means tending normally to maintain the said valve in closed position, a fluid operated 15 motor including a cylinder and a piston movably mounted within the cylinder, and connected operatively with the said valve, a source of supply of motive fluid, a valve chamber having three ports communicating 20 with one end of the motor cylinder, with the

source of supply of motive fluid, and with the atmosphere, respectively, a double acting valve member movably mounted within the said chamber and being adapted normally to seat at the second named port to 25 close the same, and means controlled by the level of the liquid within the receptacle for operating the last named valve member to withdraw the same from the second named port and to move the same into a position 30 wherein it will seat at the third port to close the same as the liquid level falls below a predetermined position.

In testimony whereof I hereunto affix my 35 signature in the presence of two witnesses.

EMIL HANNEMANN.
